BROILER MECHANISM

Lewis Moore, Joliet, Ill., and Isaiah S. Holloway,
La Fayette, Ind.Original application January 20, 1932, Serial No.
587,726. Divided and this application November
25, 1933, Serial No. 699,679

3 Claims. (Cl. 126—41)

This invention relates to broiler mechanisms and has particular relation to mechanism of the type employed in gas cook stoves, such as that disclosed in our co-pending application Serial No. 587,726, filed January 20, 1932, of which this application is a division. While the invention will hereinafter be described as embodied in a gas cook stove, it will readily be appreciated that numerous other features are capable of valuable 10 and advantageous use in stoves of other character and employing heat otherwise generated as from kerosene, electric units, etc.

A principal object of this invention is the provision of an improved manipulative device for arranging the broiler pan at desired distances from the burners when the drawer or slide is in operative position, the improvement in this connection having regard for the appearance of the drawer and the employment of the same manipulative device for sliding the drawer or slide in or out of the compartment and for raising or lowering the pan.

Numerous other objects and advantages of the invention will be apparent as it is better understood from the following description, which, when taken in connection with the accompanying drawing, illustrates a preferred embodiment thereof.

Referring to the drawing,

30 Figure 1 is a perspective view of the stove embodying our present invention;

Fig. 2 is a partial perspective view showing the broiler slide or drawer in extended position;

Fig. 3 is a fragmentary perspective view of the 35 manipulative device for withdrawing the slide or drawer and accomplishing vertical adjustment of the pan;

Fig. 4 is a partial front elevation of such device;

40 Fig. 5 is a section taken across the square end of the adjusting shaft, showing the pendant handle in pan adjusting position; and

Fig. 6 is a partial front elevation of the broiler pan and broiler pan support.

45 In the instant embodiment of the invention it is intended that the broiling be accomplished in a broiler compartment 131, in the top of which is arranged the burner 51. The material to be cooked is adapted to be adjustably supported at 50 varying distances from the burner 51 in a slide or drawer generally depicted in Fig. 2. This slide or drawer comprises a vertical front wall 132 adapted to close the opening into the broiler compartment and permanently connected to a 55 frame work or a skeleton structure which slides

into and out of the broiler compartment. This skeleton structure comprises side rails 133 connected at their front ends to the front wall 132 and at their rear ends to a back cross member 134.

Two rock bars or rods 135 having bearing at the front in the wall 132 and at the rear in a bearing casting 136 are secured to the rear cross member 134. Each of the rods 135 is provided with an upwardly extending arm 137 at the 10 front and at the rear, the two arms at the front and in the back being pivotally connected at 138 to a cross member 139. Upon the two cross members 139 thus provided the broiler pan 141 is adapted to be arranged. One of the arms 137 at each end of the slide or drawer is connected to a link 142 in turn connected by pins 140 arranged through a slot 143 in the companion member 139. The dimension and arrangement of the parts are such that the pins 140 move substantially vertically as the arms 137 are rocked to adjust the height of the broiler pan. These pins engage appropriately arranged notches 144 in the flanges 145 formed at the ends of the broiler pan and serve to confine the broiler pan 20 to substantially a straight vertical movement in the adjustment.

25 Rollers 146 are or may be provided upon the ends of the bars 139 to facilitate movement of the bars with respect to the broiler pan. The 30 left hand rod 135 is provided with a third arm 147, arranged in or behind the front wall 132 of the broiler drawer or slide, and a spring 148 is provided to counter balance the movement of the 35 pan.

A shaft 151 is arranged through an escutcheon bearing 152 mounted on the front of the drawer or slide and this shaft is provided at its inner end with a fixed laterally extending arm 153, having a pin 154 arranged through a slot 155 in the upper end of the arm 147. The end of the shaft 151 extends through the escutcheon bearing 152 and is formed of rectangular cross section outwardly or forwardly of the bearing, as indicated at 156. The rectangular portion of the shaft is tapered 40 as illustrated and is bent at 157 rearwardly to a T stop 158. A pendant handle 159 having a rectangular eye 161 is arranged upon the end of the shaft. The dimensions of the eye 161 and the rectangular portion 156 of the shaft 151 are 45 such that the handle may be fitted to the shaft rod to turn it by rotation of the handle in a horizontal plane to raise and lower the broiler pan, as will be readily understood.

50 The handle 159 may also be grasped and pulled 55

forwardly or swung to a position to pull the slide or drawer out from the broiler compartment. It will be apparent that in every position of the broiler pan the handle 159 will hang downwardly as illustrated in Fig. 1 of the drawing. A similar handle 162 is provided on the oven door.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

We claim:

1. In a stove, a broiler slide having vertically adjustable means for supporting a broiler pan, a device arranged at the front of the slide for withdrawing the slide and operating the means for adjusting the broiler pan, said device including a rotatable shaft and a pendant handle, said handle being engageable with said shaft and rotatable in one plane to operate said vertically ad-

justable means, and being rotatable in a different plane to a position in substantial axial alignment with said shaft to withdraw the slide.

2. In a stove, a broiler pan, and means for supporting said pan and for moving it vertically, 5 said means normally tending to shift said pan laterally and including a member for preventing such lateral shifting of said broiler pan during the vertical movement thereof, comprising a lever having a pin and slot connection with said broiler 10 pan.

3. In a stove, a shaft rotatably mounted therein and having a tapered, rectangular portion at the forward end thereof, bent rearwardly and terminating in a stop member, and a pendant 15 handle mounted on said shaft and having a rectangular eye normally engaging the shaft adjacent said stop member and hanging downwardly therefrom, and adapted to engage the base part of said tapered rectangular portion to rotate said 20 shaft.

LEWIS MOORE.
ISAIAH S. HOLLOWAY.
